UNITED STATES PATENT OFFICE

ROBERT PENMAN, OF BARBERTON, OHIO, ASSIGNOR TO THE BABCOCK & WILCOX COMPANY, OF BAYONNE, NEW JERSEY, A CORPORATION OF NEW JERSEY

CALKING MACHINE

Application filed July 11, 1928. Serial No. 291,998.

This invention relates to calking machines and more particularly to a support for a calking machine adapted for use in calking a seam between a nozzle or the like, and the sheet of metal to which the nozzle is secured. The invention will be better understood from the following description and the accompanying drawings, in which I have shown a selected embodiment of the invention, and in which

10 Fig. 1 is a partial longitudinal section through a drum showing one use to which the invention may be put.

Fig. 2 is a view on a larger scale, showing the device appearing in Fig. 1.

15 Fig. 3 is a view taken on the line 3—3 of Fig. 2.

Fig. 4 is a view taken on the line 4—4 of Fig. 2.

20 Fig. 5 is a view taken on the line 5—5 of Fig. 2.

For the purposes of illustration, I have shown my invention as employed to calk a seam between a sheet in the form of a drum and a nozzle secured to the drum. The drum sheet is indicated at 1 and, as shown, has an opening, the edge of which is designated 2. Secured to the drum adjacent the opening is a nozzle outlet 3, the securing means being omitted from the drawings. Such means may 25 comprise welding, riveting, or any of the well-known forms of attachment.

Disposed in the nozzle 3 is a bushing comprising a hub 4 and a plurality of arms 5 extending outwardly therefrom. This bushing, and more particularly the arms, are of such size as to fit the particular nozzle with which the device is being used. The bushing may be retained in position in the nozzle by 30 any suitable means such as a plate 6 secured to the nozzle as by bolts 7.

As plainly shown in the drawings, the hub 4 has a central bore 8 within which is received a post 9, the form of which is best seen in Fig. 3. It will be noticed that the post has two substantially parallel portions offset with respect to one another, and the upper portion is adapted to support a calking tool substantially over the lower portion, so that the tool 45 will be disposed substantially at the center

of the nozzle. The reason for this construction will be made apparent later.

Slidably mounted on the upper end of the post is a collar 10 which may be secured in any desired position on the post by means of a set screw 11. The collar has a transversely extending member 12 at the end of which is a face plate 13 having a recess 14 within which is slidably mounted a bracket 15. This bracket has a downwardly extending arm 16 having an enlarged outer end 17 which is bored to receive the hammer 18. The bracket may be slid back and forth on the face plate 13, and may be secured in adjustable position as by means of the slotted connection best shown in Fig. 2, and which comprises a slot 19 which receives a bolt 20 which is threaded into the collar.

The upper end of the hammer has secured thereto the cap 21 which is provided with studs 23 passing through transversely extending lugs 24 on the bracket arm 16. Between the lower heads of the studs and the lugs 24, are disposed springs 25 to absorb the vibration of the hammer. The details of the hammer have not been shown because any suitable type of hammer may be used. The hammer is shown as being of the well-known type operated by air which is supplied through a hose 26, the passage of air being controlled by the valve 27. The tool operated by the hammer is shown at 28, and it will be seen that by the above construction, this tool is supported on a post which is disposed substantially at the center of the opening surrounded by the seam which it is desired to calk, this seam being the one between the edge 2 and the nozzle.

The bushing may be secured in the nozzle by any suitable means such as the set screw 29, which is turned outwardly till its head engages the wall of the nozzle. Then, as the hammer is operated to calk the seam, the post 9 may be rotated in the bore 8. Preferably, the sheet is disposed horizontally, and it will be noticed that the bottom 29 of the post 9 does not touch the plate 6, and therefore the entire weight of the assembly is transmitted through the tool 28 to the seam. This weight gives the necessary reaction to

the hammer blows to properly calk the seam. The tool is also substantially over the center of the opening, so that upon rotation of the post the tool will always be in proper position with respect to the seam.

6 I claim:—

1. In a calking device for use with a sheet having an opening therein with a seam adjacent said opening, a support rotatably carried by said sheet and disposed substantially at the center of said opening, and a calking tool on said support and adapted to calk said seam.
2. In a calking device for use with a sheet having a nozzle secured thereto and adjacent an opening therein, a post supported in said nozzle and extending through said opening, and a calking tool supported on said post and adapted to calk the seam between said nozzle and said sheet.
3. In a calking device for use with a sheet having a nozzle secured thereto and adjacent an opening therein, a post supported in said nozzle and extending through said opening, a calking tool supported on said post and adapted to calk the seam between said nozzle and said sheet, and means for adjusting said tool lengthwise and laterally of said post.
4. In a calking device for use with a sheet having an opening therein and a nozzle secured to said sheet and substantially concentric with said opening, a bushing disposed in said nozzle and having a bore substantially at the center of said nozzle and opening, a post rotatably mounted in said bore and having an offset portion extending through said opening, and a calking tool supported on said offset portion and adapted to calk a seam between the sheet and the nozzle.
5. In a calking device for use with a sheet having an opening therein and a nozzle disposed substantially concentric with said opening and secured to the sheet, a post having parallel portions offset with respect to each other, means for securing one of said offset portions substantially at the center of said nozzle and in a position wherein the other offset portion will extend on the other side of said sheet from said nozzle, and a calking tool supported on said second offset portion on the same side thereof as said first offset portion.
6. In a calking device for use with a sheet having an opening therein and a nozzle disposed substantially concentric with said opening and secured to the sheet, a post having parallel portions offset with respect to each other, means for securing one of said offset portions substantially at the center of said nozzle and in a position wherein the other offset portion will extend on the other side of said sheet from said nozzle, and a calking tool supported on said second offset portion and adapted to calk a seam between the sheet and the nozzle.

7. In a calking device for use with a sheet having an opening therein and a nozzle disposed substantially concentric with said opening and secured to the sheet, a post having parallel portions offset with respect to each other, means for securing one of said offset portions substantially at the center of said nozzle and in a position wherein the other offset portion will extend on the other side of said sheet from said nozzle, a calking tool supported on said second offset portion and adapted to calk a seam between the sheet and the nozzle, and means to adjust said tool lengthwise and laterally of said post.

8. In combination, a post, a collar slidably mounted on said post and having a face plate thereon, a bracket slidably mounted on said face plate and having an arm provided with a bore, a calking tool slidably mounted in said bore, and a spring acting between said bracket and said tool to absorb vibrations in the tool.

9. In a calking device for use with a horizontally disposed sheet having an opening therein and a nozzle secured to said sheet and registering with said opening, a bushing disposed in said nozzle and having a central bore, a post disposed in said bushing, and a calking tool supported by said post and adapted to calk a seam between the sheet and the nozzle, the bottom of the post in said bore being unsupported whereby the weight of the tool and the post will be transmitted through the tool to the seam which is being calked.

10. In a calking device for use with a drum having an opening therein with a seam adjacent said opening, a support rotatably carried by said drum and disposed substantially at the center of said opening, and a calking machine on said support and adapted to calk said seam.

ROBERT PENMAN.
